(No Model.)

R. B. LAVIGNE.
MEAT TENDERER.

No. 508,953.

Patented Nov. 21, 1893.

UNITED STATES PATENT OFFICE

ROSE B. LAVIGNE, OF NEW HAVEN, CONNECTICUT, ASSIGNOR TO THE
LAVIGNE & SCOTT MANUFACTURING COMPANY, OF SAME PLACE.

MEAT-TENDERER.

SPECIFICATION forming part of Letters Patent No. 508,953, dated November 21, 1893.

Application filed February 24, 1893. Serial No. 463,541. (No model.)

To all whom it may concern:

Be it known that I, ROSE B. LAVIGNE, of New Haven, in the county of New Haven and State of Connecticut, have invented a new Improvement in Meat-Tenderers; and I do hereby declare the following, when taken in connection with accompanying drawings and the letters of reference marked thereon, to be a full, clear, and exact description of the same, and which said drawings constitute part of this specification, and represent, in—

Figure 1, a view in side elevation of a meat-tenderer constructed in accordance with my invention; Fig. 2, a view thereof in vertical transverse section on the line $x-x$ of Fig. 1; Fig. 3, a similar view on the line $y-y$ of the same figure; Fig. 4, a reverse plan view showing the dodging or alternation of the knives.

My invention relates to an improvement in meat-tenderers, the object being to produce a simple and effective device, adapted to be readily cleaned.

With these ends in view, my invention consists in the combination, in a meat-tenderer, with the frame thereof, of two knives connected therewith in parallel planes, but separated from each other, and one of them being pivotally connected with the frame, a spring-actuated reciprocal clearer mounted in the frame, and located in the space between the said knives, and means for normally holding the knives in their closed or operating positions.

My invention further consists in certain details of construction and combinations of parts as will be hereinafter described, and pointed out in the claims.

In carrying out my invention, I employ a frame A, provided at one end with a handle A', and constructed with four lugs A² A², A³ A³, depending from its lower edge. To these lugs I pivotally attach two knife-holders B B', the former being furnished with corresponding lugs b b, formed on its upper edge, while the latter has two corresponding lugs b' b' extending upward from its upper edge. The said lugs of the frame and the knife-holders are arranged to fit together in line, so as to receive two horizontal pins C C, which thus pivotally connect the knife-holders with the frame. Two long knives D D are respectively

secured by means of rivets d, to the knife-holders, which are thereto vertically slotted, as shown in Figs. 3 and 4 of the drawings. The lower edges of the said knives are vertically slotted to form long teeth d', the lower ends of which are sharpened, the teeth of one knife being dodged or alternated with those of the other. The said knives are located in parallel planes with a space D' between them. 55 This space receives the spring-actuated reciprocal clearer E, which consists of a long rod, having a straight main-portion a little longer than the length of the knives, and two legs bent upward at a right angle to its main-portion, and passing through sleeves F F, forming extensions of the lugs A³ A³, of the frame, the said legs being reciprocal in the said lugs for permitting the main-portion of the clearer to play up and down between the 60 knives. Springs G G respectively encircling the legs of the clearer, and interposed between the lower faces of the lugs, and pins g, located in the clearer, exert a constant effort to throw the clearer to the limit of its outward movement, in which it stands about even with the edges of the knives, the limit of this movement being determined by pins g' g' located near the ends of the legs, and arranged to engage with the upper faces of 65 the said lugs. A thumb-screw H, mounted in the knife-holders B B' about midway of the length thereof, is provided for holding them in their normal or operating positions, in which they are prevented from swinging with 70 respect to the frame, by means of the clearer E, which, although it is reciprocal in the plane of the knives, is fixed in the frame so far as lateral or swinging movement is concerned. 75

In the use of the device, the clearer will be 80 pushed inward as the knives enter the meat, under the force of the blow given to the device, but when the force of this blow has been spent, and the device is lifted, the springs of the clearer will reassert themselves and 85 push it outward to its normal position, whereby the knives will be assisted in being cleared from the meat. When it is desired to clean the device, the thumb-screw H, is turned so as to disconnect the two knife-holders, thus 90 permitting one of the knives to be swung away from the other, and giving ample room 95

for cleaning the space between them. If preferred, only one of the knife-holders may be pivotally connected with the frame, although the construction shown will probably be found 5 most convenient. I would therefore have it understood that I do not limit myself to the exact construction herein shown and described, but hold myself at liberty to make such changes and alterations as fairly fall 10 within the spirit and scope of my invention.

I am aware that a meat-tenderer having two parallel knives with dodged or alternated teeth, and a spring-actuated clearer located between the same, is old, and I do not therefore claim that construction broadly. 15

I am also aware that a meat-tenderer having two parallel series of knives of which one series is adapted to be moved away from the other, is old.

20 Having fully described my invention, what I claim as new, and desire to secure by Letters Patent, is—

1. In a meat tenderer, the combination with the frame thereof, of two knives connected therewith in parallel planes, but separated from each other, and one of them being pivotally connected with the frame, a spring-actuated reciprocal clearer mounted in the frame, and located in the space between the 25 30 said knives, and means for normally holding

the knives in their closed or operating positions, substantially as described.

2. In a meat-tenderer, the combination with the frame thereof, of two knives pivotally connected with the said frame in parallel planes, 35 but separated from each other, a spring-actuated reciprocal clearer mounted in the frame, and located in the space between the said knives which it holds against lateral movement, and means for normally holding the 40 knives in their closed or operating positions.

3. In a meat-tenderer, the combination with the frame thereof, of two knife-holders pivoted to the said frame, two knives respectively attached to the said holders, a spring-actuated reciprocal clearer located between the knives, which it holds against lateral movement, and means for normally holding the knives in their closed or operating positions, substantially as set forth, and whereby 45 the knives may be separated for cleaning the device.

In testimony whereof I have signed this specification in the presence of two subscribing witnesses.

ROSE B. LAVIGNE.
